UNITED STATES PATENT OFFICE.

HAROLD S. LABOMBARDE, OF NASHUA, NEW HAMPSHIRE.

MACHINE FOR MAKING CARTONS.

Application filed February 6, 1924. Serial No. 690,997.

To all whom it may concern:

Be it known that I, HAROLD S. LABOMBARDE, a citizen of the United States, and resident of Nashua, in the county of Hillsboro and State of New Hampshire, have invented certain new and useful Improvements in Machines for Making Cartons, of which the following is a specification.

This invention relates to the production of paper or pasteboard boxes, and has particular reference to the manufacture of corrugated paper cartons of the type comprising a blank cut and creased to provide four wall sections and a relatively narrow edge section or flap at one edge which, when the blank is folded on two of its crease lines, is over-lapped upon the opposite edge of the blank and secured thereto.

Some boxes or cartons of this type have been made with the lapped joints secured by glue (a generic term used herein as applicable to any suitable adhesive), and others have been made with the lapped joints secured by a row of wire fastenings. Such cartons, when they are to be used for shipping or storing more or less bulky or heavy goods, are made of corrugated paper which always comprises two or more layers of paper having parallel air spaces. The paper employed is not tough, and this fact and the pressure of the air spaces renders it impossible for wire fastenings to reliably prevent relative slipping of the material at the lapped joint. And the same characteristics of the paper render it impossible to effect a reliably inseparable seam by means of glue alone.

One of the objects of my invention is to provide a machine for making boxes or cartons of this type with lapped joints which are seamed by glue and also by fastenings which pass entirely through the two layers of lapped material, whereby strong and durable joints are provided.

Another object is to provide machines of this character in which the feeding of the blanks is timed to coordinate with the timing of operation of the stitching or stapling mechanism.

With these and other objects in view, as will be explained, the invention consists in the construction and combination of parts substantially as hereinafter described and claimed.

Of the accompanying drawings:

55

Figure 1 is a side elevation, partly in section, of a complete machine embodying my invention.

Figure 2 is a detail view, on a larger scale than Figure 1, of parts which effect timing of the feed of the blanks.

Figure 3 is a plan view of the machine.

Figure 4 represents a section on line 4-4 of Figure 3.

Figures 5, 6, and 7 are views illustrating work performed by the machine.

Similar reference characters designate similar parts in all of the views.

At one end of a suitable frame 12 is a feed mechanism for cut and creased blanks such as indicated at *a* in Figure 5. A pile of such blanks, stacked between adjustable side plates 13 (Fig. 3), rear strips 14, and a front gage strip or plate 15 (Fig. 1) is supported by suitably mounted rolls 16 with the front edge of the lowermost blank of the pile capable of intermittently resting, as presently explained, on one or more continuously rotating feed wheels 17 having a friction periphery spaced sufficiently below the lower end of the gage 15 to permit one blank at a time to pass out to the carrier and folding belts. By intermittently acting upon the lower blank to lift it out of contact with the feed wheel 17 and elevate its front edge above the space below the strip 15, feeding is arrested until again lowered. The mechanism for effecting this operation comprises a roll or rolls 18 carried by arms 19 of a rock shaft 20 (Figs. 1, 2, and 3) mounted in bearings supported by the side portions of the frame, said shaft having another arm 21 to which a spring 22 is connected. An adjustable stop screw 23 (Fig. 1) behind the arm 21 determines the lowermost position for the lifting rolls 18.

A link 24 is connected at one end to the arm 21 and at the other end (Fig. 2) has a loop 25 riding on a roll 26 carried by a shaft 27 having a cam 28 which acts on a small roll 29 at the end of loop 25 whereby, coacting with the spring 22, the arms 19 and their rolls 18 are caused to alternately occupy the position indicated by the full and dotted lines in Figures 1 and 2. A portion of the rod 24 is broken away in Figures 1 and 3 to avoid confusion with other parts

at the right in those figures. It will now be understood that a blank is fed only when the rolls 18 are lowered. As will be explained hereinafter, the shaft 27 which carries the cam 28 is so timed as to its rotation, relatively to the operation of the stitching or stapling mechanism and the parts which bring the folded blanks successively to position to be operated upon 5 by said mechanism, that the fastenings are applied in the correct positions longitudinally of the joint as indicated by Figure 7.

Near the shaft 30 of the feed wheel 17 is a shaft 31 on which pulleys 32 are mounted 15 to rotate therewith but capable of being adjusted longitudinally thereof. On the shaft 27 at the other end of the machine pulleys 33 are similarly mounted. A pair of lower or carrier belts 34 are mounted on the pulleys 32, 33, and also run over suitable tightener pulleys 35. The upper stretches of said belts run over small rolls mounted in cage bars 36 which are laterally adjustable on the shafts 31, 27, by means of screws 37 25 having crank handles 38. The two screws at each side of the machine are preferably provided with sprockets geared together by a chain 39. The ends of the cage bars 36 are so connected with the pulleys carried by 30 the shafts 31, 27 that when said bars are adjusted to suit different widths of blanks, the pulleys and the belts mounted thereon are also adjusted.

The side panels of the blanks are turned in by twisted folding belts 40 which, at one end, are mounted on pulleys 41 carried by a driven shaft 42 above the shaft 27, and at the other end by pulleys 43 alongside of the pulleys 32 and on the same shaft 31 which carries said pulleys 32 (Figs. 1, 3, and 4). So far as I am aware, I am the first to provide a folding machine in which both carrier belts and folding belts are mounted at one end on pulleys all of which are carried 45 by the same shaft whereby equal speed of travel of the belts is ensured.

Properly located guiding pulleys for the twisted folding belts are indicated at 44, 45, 46.

50 All of the pulleys for the upper or twisted belts are so mounted and connected with the cage bars 36 that when the said bars and the lower or carrier belts are adjusted, the upper ones are simultaneously adjusted.

55 Mounted and laterally adjustable on two upper tie bars 47 are three brackets, the two outer ones being indicated at 48 in Figure 3 and the middle one at 49. The outer ones 48 support the cage bars 50 in which 60 are mounted small idler rolls which hold the blanks down on the lower carrier belts in that portion of the machine where the side panels of the blanks are first turned up by the folding belts. Said cage bars 50 65 have extensions or fingers 51 over which the

side panels are folded. The middle bracket 49 supports a long finger 52 which extends nearly to the delivery end of the machine, the portion which is to act as an anvil or clinching strip as presently described being 70 thin. The outer sides or edges of the cage bars and fingers 51 ensure folding of each blank on two of its crease lines as indicated by Figure 6.

75 Each blank has a narrow edge flap a' which, as the blank issues from the feeder, passes over and in contact with a glue wheel 53 carried by a suitably driven shaft, said wheel taking glue from a receptacle 54. Lateral adjustment of the glue applying device is provided for by a screw 55 having a hand crank 56 (Fig. 3).

80 Mounted on sprockets carried by a shaft 57 and by the shaft 27 (Fig. 1) are two chains 58 having pins 59 at properly spaced intervals, said chains being driven at a slightly slower speed of travel than the belts 34, 40.

85 The two folding belts are so twisted that as each blank passes beyond the point where 90 it reaches the condition of fold shown by Figure 6, the panel having the flap a' , which has received glue on its under surface, reaches position so that the margin of the panel at the other side is folded on top of 95 the said glue flap a' as indicated by dotted lines in Figure 7. Each blank, as it is completely folded, with its middle portion below the thin anvil strip 52 and its overlapped margins above said strip, is caused 100 by the belts to contact with a pair of chain pins 59 in front of it, the belts then slipping a little past the folded blank and keeping it squared up against said pins. The pairs of pins are so spaced that a second 105 pair can not reach the rear edge of a folded blank before the latter is discharged onto the belt 60 of a suitable stacking mechanism.

110 The wire stitching or stapling mechanism is indicated as a whole at 61. As it is a mechanism which specifically, could not be claimed in a patent for the features which I have invented, it is unnecessary to illustrate its details herein. The mechanism

115 which is outlined is the well-known "Saranac" multiple-head stitcher, but it might be some other type so far as the present invention is concerned. It is sufficient for the present to state that the wire fastenings are delivered through nozzles 62 and driven 120 through the overlapped and glued portions of each folded blank, such fastenings being indicated at a^2 in Figure 7. The fastenings are clinched against the anvil strip 52 hereinbefore referred to, said strip being, in 125 practice, supported by a suitable rigid plate not necessary to illustrate, a space being provided, of course, for the passage of the middle or main portion of the folded blank to pass along between such rigid plate and 130

the anvil strip. The rigid plate referred to is supported by a bar 71 hereinafter referred to.

While explanation of the details of the stitching or stapling mechanism is unnecessary, it is important that the chosen number of its units shall act in time with the arrival of a folded blank beneath the nozzles 62. The drawings indicate ten units and ten nozzles. The well-known Saranac machines referred to include means for causing only selected units to simultaneously operate. Figure 7 indicates need for but three units, but it will be readily understood that longer blanks or boxes might require the operation of a greater number of units.

Assuming now that the main shaft 63 of the entire machine is suitably driven, as by a belt operating one of the pulleys 64 (Fig. 3), gearing is provided which will ensure the proper relative timing of operation of the feeder, folder, pin-carrying chains, and stitcher. Such gearing comprises a pinion 65 carried by the drive shaft 63 and meshing with a gear carried by shaft 27 (Fig. 1), the latter driving the chains which carry the carton-locating pins 59. The same shaft 27 drives the lower belts which in turn drive the shaft 31. Through the folding belts, said shaft 31 drives the shaft 42. In practice, however, it may be desirable to also provide the shafts 27, 42, with intermeshing gears. The shaft 42 has a pinion 66 meshing with the lower one of the two intermeshing gears 67, 68, of the stitcher, said gears operating as usual to effect the operation of the selected units of the stitcher at predetermined intervals. The relative proportions of the pinions and gears are such as to ensure simultaneous operation of the stitcher units once just as a pair of chain pins permit a glued and folded blank to arrive in position to receive fastenings as indicated at α^2 in Figure 7. The momentary pressure of the stitcher plungers upon the blank may temporarily arrest the blank, but no injury can be effected because before the next pair of chain pins 59 can catch up with the rear edge of the folded blank, the stitcher plungers will have risen and the upper and lower belts then effect delivery of the folded, glued, and stitched carton.

In order that the stitching mechanism may be laterally adjusted to secure proper location of the fastenings α^2 , especially when different sizes of blanks are to be operated upon, said mechanism is supported on two upper transverse bars 69, and the anvil supporting plate hereinbefore referred to and indicated at 71 is supported on two lower transverse bars 70. Screws 72 extend into threaded members of the upper part of the stitching mechanism and screws 73 extend

into threaded portions of the plate 71. Chains 74 connect sprockets secured to the upper screws with sprockets secured to the lower screws, and a chain 75 connects sprockets secured to the two lower screws, whereby all of said screws may be simultaneously and equally actuated by operating either one of said chains or by operating a handle or wrench applied to either of the four screws.

To ensure travel of each blank from the feeder onto the carrier belts, I may employ rolls 77 carried by a shaft 76 (Figs. 1 and 4).

As the operation of the several parts of the machine have been explained in connection with the descriptions of the structures of such parts, an explanation of the operation of the machine as a whole will be unnecessary.

Having now described my invention, I claim:

1. A carton-making machine having means for folding blanks with overlapping portions, and means for securing said overlapping portions both by glue and a row of fastenings.

2. A machine for making cartons, having means for applying glue to a portion of each blank, means for folding the blank with a glue-lapped joint, and means for applying a row of metallic fastenings to said joint.

3. A machine of the character described comprising a blank feeder, mechanism for folding the blanks with their opposite marginal portions over-lapping each other, mechanism for applying separate fastenings to the overlapped portions, and means for timing the operation of the feeder to accord with the operation of said fastener-applying mechanism.

4. A machine having means for driving wire fastenings, a feeder for blanks, mechanism for successively folding the blanks with their opposite marginal portions over-lapping each other and delivering them with the overlapping portions in position to be operated upon by the wire fastening means, and means for coordinating the feed of the blanks with the operation of the wire fastening means.

5. A blank folding machine having a pair of carrier belts, a shaft having pulleys for said belts, a feeder adjacent said shaft for delivering blanks to said belts, twisted folding belts mounted on pulleys carried by said shaft adjacent the feeder, and rolls for holding the blanks in contact with the carrier belts during the first portion of their travel thereon.

6. In a machine of the character described, a pair of carrier belts, a pair of bars extending partially along the belts and above them, folding instrumentalities for acting on portions of blanks at the outer

- sides of said bars, a strip between said bars onto which the marginal portions of the blanks are folded and overlapped and means for applying fastenings to the overlapped portions of the blanks while said portions are supported by said strip.
7. A machine of the character described, having an intermittently operative wire-fastening mechanism, means for folding blanks with their opposite marginal portions over-lapping each other and delivering them to position for said overlapping portions to be operated upon by said mechanism, and means for ensuring correct position of each folded blank relatively to said wire-fastening mechanism.
8. A machine of the character described, having an intermittently operative wire-fastening mechanism, means for folding blanks and delivering them to position to be operated upon by said mechanism, and a pair of chains having pins to be engaged by said blanks to determine the position of each blank to receive its wire fastenings.
- 25 9. A carton making machine having means for causing blanks to travel while being folded, a pair of chains having pins against which the front edges of the folded

blanks abut, and mechanism for applying fastenings to each folded blank while it is 30 in contact with said pins.

10. A machine of the character described comprising a blank feeder, means for applying glue to a portion of each blank, means for folding each blank with a glue-lapped joint, a pair of chains having pins against which each blank is delivered by the folding means, and means for applying fastenings to said lapped joint while the blank is in contact with the chain pins. 40

11. In a machine having means for folding blanks and means for applying metal fastenings thereto, means for adjusting the lateral positions of both the folding means and the fastener-applying means. 45

12. In a machine having means for folding blanks and means for applying metal fastenings thereto, means for adjusting the lateral positions of both the folding means and the fastener-applying means, said adjusting means comprising a plurality of screws having connections for ensuring their equal operation. 50

In testimony whereof I have affixed my signature.

HAROLD S. LABOMBARDE.
